UNITED STATES PATENT OFFICE

161,997

DISPLAY CASE FOR THREE ELECTRIC SHAVERS

George S. Birse, Chicago, Ill., assignor to Lawrence A. Westerberg, Skokie, Ill.

Application March 23, 1950, Serial No. 8,726

Term of patent 3½ years

(Cl. D80—11)

To all whom it may concern:

Be it known that I, George S. Birse, a citizen of the United States, residing at Chicago, State of Illinois, have invented a new, original, and ornamental Design for Display Case for Three Electric Shavers, of which the following is a specification, reference being had to the accompanying drawing, forming a part hereof.

I claim:

The ornamental design for a display case for three electric shavers, as shown.

GEORGE S. BIRSE.
